UNITED STATES PATENT OFFICE.

WILLIAM H. SWARTZ AND OSCAR B. RICHARDS, OF YORK, PENNSYLVANIA, ASSIGNEES
TO GENERAL MACHINE WORKS, OF YORK, PENNSYLVANIA.

KNITTING-MACHINE.

1,327,122.

Specification of Letters Patent.

Patented Jan. 6, 1920.

Application filed June 29, 1918. Serial No. 242,580.

To all whom it may concern:

Be it known that we, WILLIAM H. SWARTZ and OSCAR B. RICHARDS, citizens of the United States, residing at York, in the county of York and State of Pennsylvania, have invented certain new and useful Improvements in Knitting-Machines, of which the following is a specification, reference being had therein to the accompanying drawings.

This invention relates to improvements in knitting machines, and particularly to that type disclosed in U. S. patent to Ruth, No. 715,154, issued December 2, 1902.

It is to be understood that in the art to which our invention relates, it is a common practice to employ two independent devices involving two separate and independent movements, actuated by two independent sources, to adjust the needles for causing the character of the stitches to be changed.

The object of our invention is the construction of a simple and efficient device, which will be operated from the same source as the other, or companion, device usually employed in an old structure known to the art, for obtaining the adjustment of the needles by a simple, single lever and link adjustment hereinafter specifically described.

With this and other objects in view, the invention consists of certain novel constructions, combinations and arrangement of parts, as will be hereinafter fully described and claimed.

35 In the drawings:

Figure 1 is a view, in side elevation, of a knitting machine, showing our improved device assembled therewith.

Fig. 2 is a sectional view taken on the line 40 2-2, Fig. 1, looking in the direction of the arrows, and showing particularly our improved device, while

Fig. 3 is a view, in side elevation, of the same.

45 Fig. 4 is a perspective view of a cam collar, or eccentric forming part of our invention.

Fig. 5 is a fragmentary view in elevation of a knitting machine showing the cylinder needles and the dial needles.

50 Fig. 6 is a fragmentary, transverse, sectional view of the structure shown in Fig. 1, showing particularly the cam post and the vertically-movable cam attached thereto.

55 Fig. 7 is a bottom plan view of the dial cap.

There are a number of devices known to the art used to press the cam-post 1 down, (for example, such as that shown in the U. S. Patent No. 715,154, to G. W. Ruth, granted December 2, 1902) and thus lower the top ends of the needles 2 during the critical period of knitting, but all of these old devices are actuated and controlled by a lever that is a part of a device to operate cam-post 1, and which is eliminated by our improved device.

Our device comprises the primary cam-link 3 and the auxiliary link 4 pivotally connected by means of bolt 5, the outer end 6 of link 4 being adapted to engage the top of the cam-post 1.

The outer link 4 is of a bell-crank type, and the link 4 is pivotally mounted, at 7, upon a post 8 of the plate 9, which plate 9 is suitably secured to the base 10 of the knitting machine.

The inner end of the cam-link 3 is provided with an annular ring 11, which annular ring 11 fits over the cam-extension 12 of the cam-collar 13.

The vertical rotary post or shaft 14 carries the cam-collar 13, and by means of a set-screw or fastening member 15, the cam-collar 13 is secured in an adjusted position upon the vertical rotary post or shaft 14.

Fixedly secured to shaft 14 is an operating lever 16, and by swinging the operating lever in the arc of a circle, the cam-extension 12 of the cam-collar 13 will be rotated within the ring 11 and cause a horizontal sliding movement of the cam-link 3 for swinging the bell-crank link 4, for moving the outer end 6 of said link 4 in a vertical plane with respect to the cam-post 1.

The operation of the complete device is as follows:

The lever 16 is thrown or swung, causing the post or shaft 14 to revolve or turn only a portion of the circle (approximately one-eighth), and this slight movement of the cam or eccentric 13 causes the links or arms 3 and 4 to move forward, as indicated by dotted lines, Fig. 3, which movement results in the end 6 of the bell-crank link 4 to press on the head 1, thus lowering the needles until the critical knitting stage (welt) is passed.

It is to be understood that the movement of the lever 16 is the beginning of the entire movement, which causes the knitting of the welt. All other old devices to lower the

needles, operated by two separate devices in place of lever 16, are uncertain, because, should either one lever or device get out of order, and refuse to join in the operation 5 with its companion device at the critical time, when the apparatus controlled by lever 16 starts to make the welt, then the welt knitting will proceed without its ally (the other device) and the result will be disastrous.

With our invention, both devices are actuated by the same lever 16, that is, besides the link device constituted by links 3 and 4, a link 17 (Fig. 1) is attached to and near the 15 upper end of the post or shaft 14 and operates the device that controls the other set of needles of the machine, and if said lever 16 is operated at all, then both of the devices, connected to the post or shaft 14, will proceed to work simultaneously, and if the said lever fails to encounter the member that should operate it, then neither device can start working, and there will be no disaster at all, the only result will be no 20 welt—no torn yarn or broken needles, or great loss of time necessary to repair the same. Referring to Fig. 5, when the plain portion of the article or garment has been knitted, such for instance, as the sleeve, 25 the tops or hooks of the cylinder needles always stand in a line shaped as at 18. This V-shaped arrangement 18 is caused by the butts 19 of the needles riding under the cam 20, which cam 20 is fastened by screws 20^a 30 to the vertically-movable cam post 1. It is desired to "lengthen the stitch", as the trade terms it, at the time the welt, or any other portion of the knitted fabric that is thicker or heavier than the body or plain portion, is 35 being knit, because by so lengthening the stitch more space is secured between the ends, or hooks, or the horizontal dial needles, and the vertical cylinder needles, thus allowing 40 the thick portion (already knitted) to pass between all the hooks of the dial and cylinder needles without breaking the needles.

When the cam 20 is depressed, the hooks of needles follow a line as at 21, Fig. 5, and 45 the butts of some of the needles are depressed as at line 22^a.

Referring to Fig. 7, the dial cap 20^b, and its attendant parts, is to actuate the needles of the dial. During the knitting of the plain 50 portion of the fabric, the butts of the dial needles travel in the groove 23 in the direction of the arrows, and the shape of this groove causes the ends or hooks of the needles to assume a line 24 (dotted) exactly 55 the same as groove.

Attached to a rocker arm at the top end of rotatable shaft 14 is said link 17, and this link 17 is attached to a rocker arm on the cam pin 17^a, which pin is attached at its 60 lower end to the wing or swinging cam 25.

When shaft 14 is slightly rotated, this swinging cam 25 is moved to a position shown by dotted line 26 (Fig. 7), changing the shape of groove 23 to that shown by dotted line 23^a and thus causing the ends on 70 hooks of needles to assume a line as at 27 (dotted), and while at this position all the machines (as it is well known to the trade) will knit welts only until swinging cam 25 is brought back to its former position as 75 shown by solid lines (Fig. 7), when plain ribbed fabric will be knitted again.

Now, to sum the matter up briefly, when shaft 14 is rotated slightly, the attached link 17 moves cam 25, causing its attendant dial 80 needles to begin to knit the welt, the bell-crank link 4 and cam-link 3 are actuated simultaneously causing the end 6 to depress cam post 1, causing the cam 20, carried thereby, to depress the attendant cylinder 85 needles to such a position as will allow the welt of the fabric, or thick knitted portions, to "go through", as the trade puts it, to prevent the thick fabric from clogging and breaking needles. During this operation, 90 the cylinder needles hold their loops. This is how and where the coöperation is accomplished.

What we claim is:

1. In a knitting machine, the combination 95 with a support, of a rotatable shaft mounted upon said support, a needle-actuating, swinging cam carried by said support, means connecting said shaft and cam, a needle-actuating, vertically-movable cam 100 carried by said support, and a bell-crank and eccentric link device mounted upon said support and coöoperating with means assembled with the rotatable shaft and the vertically-movable cam for operating the vertically movable cam when said shaft is rotated, whereby both cams are simultaneously actuated.

2. In a knitting machine, the combination 110 with a support, of a rotatable shaft mounted upon said support, a needle-actuating, swinging cam carried by said support, means connecting said shaft and cam, a vertically-movable cam post mounted upon said support, a needle-actuating cam secured to said 115 post, an eccentric link mounted upon said rotatable shaft, an eccentric collar mounted upon said shaft and having a portion positioned within said eccentric link, a bell-crank link pivotally mounted upon said support and connected to said eccentric link, and said bell-crank link having a portion 120 overhanging the cam post, whereby, when the rotatable shaft is operated, the bell-crank link will be operated for depressing 125 said cam post.

In testimony whereof we hereunto affix our signatures.

WILLIAM H. SWARTZ.
OSCAR B. RICHARDS.
